N. J., a corporation of Delaware

Application April 28, 1947, Serial No. 744,495

9 Claims. (Cl. 60—57)

1

The invention hereof relates to turbine apparatus or the like, and particularly to means having to do with the structure and operation of a turbine itself, as well as to elements associated therewith.

Among the objects of the invention are to overcome disadvantages of former devices of the above indicated character and to do so by novel effective means.

Another object is to provide a turbine, in which that portion thereof operating as the stationary means or stator having stationary vanes for directing the operating fluid to the rotor vanes, also has vanes which have some movement relative to the stationary vanes for varying the effective fluid delivery area of the spaces between the stator vanes, as in throttling the rotor between maximum and minimum throttling conditions.

Another object is to provide a turbine of the above-indicated character, which is adapted to be carried by a vehicle or apparatus having controlled movement, and in which the turbine is operative by the ram pressure resulting from such movement.

Another object is to provide a turbine which is selectively operative from a plurality of fluid sources, such as the source of ram pressure aforesaid, and a fluid pressure supply means separate from the controlled vehicle or apparatus for operating the turbine when the apparatus carrying the turbine is stationary.

Another object is to provide means which is adapted for connecting the separate fluid supply means aforesaid to conduit means of the vehicle, and is responsive to the controlled vehicle movement for disconnection from the conduit and the vehicle, whereupon the conduit is automatically closed.

Another object is to provide a novel turbine nozzle or throttling means, which is of substantially minimum size and weight.

Another object is to provide means of the above-indicated character which are simple and durable in construction, economical to manufacture, and effective in their operation.

These and other objects and features of the invention are pointed out in the following description in terms of the embodiment thereof which is shown in the accompanying drawings. It is to be understood, however, that the drawings are for the purpose of illustration only, and are not designed as a definition of the limits of the invention, reference being had to the appended claims for this purpose.

2

In the drawings:

Figure 1 is a view partially in section and partially in elevation of a structure embodying features of the invention in one form, parts also having been broken away and omitted;

Figure 2 is a view, taken from the left of Figure 1, of the structure thereof, parts being in elevation and section and others having been broken away;

Figure 3 is a fragmentary detail taken substantially along the line 3—3 of Figure 2;

Figure 4 is a fragmentary detail taken substantially along the line 4—4 of Figure 2;

Figure 5 is a developed plan of portions of a turbine indicated in Figures 1 and 2, showing stator vanes in the fully closed throttling relation thereof to the vanes of a rotor, which stator vanes are movable relative to each other;

Figure 6 is a view partially in top plan and partially in section of means whereby the turbine is separately supplied with fluid pressure when the turbine carrier is stationary, which supply may be automatically disconnected when the carrier moves as aforesaid, and as will further appear; and

Fig. 7 is a side view partially in section of the structure shown in Figure 6.

Referring particularly to Figures 1 and 2, the device comprises a unit 10 adapted to be carried by apparatus 12, Figure 6, having controlled movement, and in which the unit 10 comprises a housing 14 having ram pressure and fluid pressure inlets 16 and 18, respectively.

A vaned rotor 20, facing the ram pressure inlet 16 and positioned behind the fluid pressure inlet 18, has vanes 21 adapting it for propulsion by fluid from the inlets 16 and 18, and is provided with a shaft 23 having a partitioned or slotted portion 22.

A vaned stator 24, forwardly or to the left of the rotor 20, as shown, includes a stationary member 26 having vanes 28 next to the rotor 20 adapted to direct fluid to the rotor vanes 21. The stator 24 includes a forwardly extending casing 30. A conduit 32, as shown in Figure 2, has a portion 34 extending radially inwardly from the inlet 18 through one of the stationary vanes 28, and a portion 36 extending axially forwardly in a wall 38 of the casing 30 to the outer casing end, or left hand end of the casing as shown in Figure 1.

A vaned throttle 40, normally in an open position and journaled, as by a bearing 42, on the casing 30 for movement about the rotor axis, has vanes 44 adapted to vary the effective delivery

ery area A, Figure 5, of spaces 46 between the stator vanes 28, and is provided with linkage coacting means 48, which in this instance, is a member of substantially U-shape secured, as by screws 50 to a flange 52 of the throttle 40, and having its legs extending axially in side elevation, as seen in Figure 1, and substantially radially in end elevation, as seen in Figure 2. A spring 54 is disposed in the casing 30.

Arms 56, in the casing 30, have forward-end lateral pivot connection 58 to the forward end of the slotted shaft portion 22 and carry fly-weight rollers 60 at their rear ends for cooperation with cam elements 62 having surfaces 64 inclined to the shaft axis on which the rollers 60 ride laterally outwardly responsive to rotation of the shaft 23 to move the cam elements 62 axially forwardly against the action of the spring 54.

A push rod 66 extends along the axis of the shaft portion 22 through an end closure 68 of the casing 30 and has a hollow portion 70 in the casing 30 journaled, as by a bearing 72, about the cam elements 62. The rod 66 is axially movable by the elements 62 to compress the spring 54 against the casing end closure 68.

The linkage mechanism 74 comprises a shaft 76 journaled in bearings 78 and 80 on the closure 68, an arm 82 cooperating with the linkage coacting means 48, and an arm 84 connected to the push rod 66 by a link 86 Figure 3 and responsive to axial movement of the push rod to convert the axial movement into turning movement of the throttle 40. Fluid pressure responsive means 88, Figures 2 and 4, also mounted on the casing end closure 68, comprises a cylinder 90 and a piston 92 and is adapted to receive fluid from the portion 36 of the conduit 32 to move another arm 94 to effect turning movement of the throttle 40.

A second spring 96, Figure 2, is connected between a member 98 on the throttle 40 and a member 100 on the closure 68 to bias the throttle 40 in a normally open direction and against turning movements of the arm 82 in a throttle closing direction. Means 101 cooperating between the throttle 40 and the casing end 68 is adapted to adjust the limits of the throttle turning movement, as hereinafter explained. A cover 103, fixed at one end to the throttle 40 to turn therewith, as shown in Figure 1, is journaled at its other end on a stub shaft or pin 105 fixed to a portion 107 of the closure 68 to prevent cantilever movement of the cover and parts carried thereby, which would unbalance the throttle and other parts.

As indicated in Figure 6, supply means 102 is adapted for connection, as by means 104 hereafter explained, to the apparatus 12 to supply fluid pressure to the inlet 18, and is responsive to controlled movement of the apparatus, as in the direction of an arrow B, relative to the supply means 102 for disconnection from the apparatus.

The supply means 102 may comprise a tripod or stand 106 for supporting a fluid pressure tank 108 and having a swivel head 110 carrying a telescopic tube 112 that is adapted to be connected into means 104 carried by the vehicle 12. The tube 112 is provided with a valve 160 of the type employed in the art to stop further flow from the pressure tank 108 upon the disconnection of the tube 112 from the vehicle 12.

The means 104 comprises, in this instance a bushing 114, secured to an outer panel or wall 116 of the apparatus or vehicle 12, supporting a seal 118 and connected to a conduit 120 con-

necting with inlet 18. The conduit 120 also includes a check valve 122 opening to the fluid responsive means 20 and 88.

The supply means 102 is positionable adjacent the apparatus 12 to the end that the head 110 thereof and its associated tube 112 is rotatable through an arc D that is coplanar with the plane in which the means 104 of the apparatus 12 are positioned. Thus, the tube 112 may be slip fitted into the bushing 114 and thereby connect the conduit 120 with the tube 112 so that a separate or independent source of fluid pressure is made available for the vehicle 12 when it is stationary.

When the vehicle 12 moves in the direction indicated by the arrow B in Fig. 6, the tube 112 is rotated through the arc D by such movement. Since the direction of the movement of the vehicle 12 is tangential to rotation of tube 112 it is apparent that at some point along arc D, for example at point C, the tube 112 pulls out of the bushing 114. The check valve 122 thereupon closes the conduit 120 and the valve 160 operates to close off tank 108 to prevent the further discharge of fluid pressure therefrom.

Referring to Figure 5, the movable stator vanes 44, which have spaces 45 therebetween, are illustrated as in positions fully closing the spaces 46 between the stationary stator vanes 28, to which positions they have been moved in the direction of an arrow E, Figures 2 and 5. This is not the normal position, but has been chosen for better illustration of how an area F of each vane 44 more than fully closes the area A. In the normal position of the throttle 40, each area F is centered opposite, and substantially equal to, an area G of one of the vanes 28.

Movement of the throttle 40 between the above-mentioned closed and open positions is limited by the means 101, which comprises adjustable stop screws 124 and 126, carried by a bracket 128 on the throttle, which engage an arm 130 mounted on the casing end closure 68.

Referring to Figure 3, the arm 84 is loosely mounted on the shaft 76 and, when moved clockwise by the plunger 66, acts through an arm 132, fixed to the shaft 76, to turn the throttle 40. This arrangement is provided so that, when the piston 92 is actuated to turn the throttle, the arm 132 will move away from the arm 84, and the piston not be required to act against resistance by the spring 54. A set screw 134 is provided in the arm 132 for engaging the arm 84 and effecting adjustment between the arms.

As indicated in Figures 1 and 2, the housing 14 has an annular portion 136 surrounding a portion 138 having an annular groove or channel 140 which conducts fluid from the inlet 18 to a plurality of nozzles 142 extending diagonally rearwardly and downwardly from the forward part of the channel 140 toward the vanes 21 of the rotor 20 and distributed about the rotor axis.

The shaft 23, in this instance, carries a rotor 144 of an alternator 146, and is connected to a pump 148.

In operation, when it is necessary or desired to actuate the rotor 20 from the source or supply means 102, a valve associated with the head 110 is opened to release fluid from the tank 108, which fluid opens the check valve 122 and continues to the inlet 18, from which it travels to the channel 140, through the nozzles 142, and into the portions 34 and 36 of the conduit 32 to the cylinder 90.

With the throttle 40 normally open, as above set forth, the first burst of fluid simultaneously hits the rotor vanes 21 and escapes forward through the open spaces 46 and 45 between the stator blades for an instant until the fluid pressure passing through conduits 32 and 36 into cylinder 90 actuates piston 92, which in turn actuates arm 94 to effect turning movement of the throttle 40, until said throttle is closed. The pressure from the source 102 is regulated to maintain the throttle closed during all of the time that the turbine is being operated from such source, with the constant resulting speed of the rotor 20 being just under the speed at which the flyweights 60 actuate the throttle toward open position through the push rod 66 and other of the parts set forth.

If such operation is in effect when the apparatus 12 acquires or is given the above-mentioned movement in the direction of the arrow B, the tube 112 slips out of the bushing 114 at about the point C, the check valve 122 closes, the supply 102 is disconnected, and closed off by valve 160, the throttle 40 opens fully and the rotor 20 continues to rotate under its inertia, and ram air pressure from source 16 thereafter operates to insure continued rotation of said rotor 20 subject to regulation of the stator vane openings 46 by means of the centrifugal governor 56 actuating the push rod 66, in turn to actuate shaft 76, and links 82 and 36 to regulate the said stator openings, and the amount of ram pressure permitted to reach the rotor 20 thereby.

When the ram pressure attains a value sufficiently high so that the speed of rotation reaches a predetermined value, the throttle will start to close.

While the centrifugal governor 56 is ineffective for opening the throttle 40 due to the connection 132 so long as the throttle 40 is held in a closed position by the piston 92 under force of the auxiliary fluid pressure from the source 102, it will be seen that upon disconnection of the source 102 from the piston 92, the spring 96 will tend to bias the throttle 40 in an opening direction and the arm 132 into operative relation with arm 84. Thereafter the throttle 40 will be adjusted by the governor 56 so as to apply a ram pressure to the turbine 20 to maintain the same at a predetermined constant speed. The turbine may, of course, be operated by ram pressure, without first operating it from a separate source such as the source 102.

Although only one embodiment of the invention has been illustrated and described, various changes in the form and relative arrangements of the parts, which will now appear to those skilled in the art, may be made without departing from the scope of the invention. Reference is, therefore, to be had to the appended claims for a definition of the limits of the invention.

What is claimed is:

1. In combination, a turbine apparatus adapted to be carried by a movable vehicle, said apparatus comprising a housing having a ram pressure inlet and an inlet for receiving fluid pressure from an independent source, a vaned rotor positioned behind both of said inlets and operable in response to fluid pressure from either of said inlets, said rotor having a forwardly extending shaft, a vaned stator positioned forward of the rotor including a stationary member having a fixed vanned portion next to said rotor for directing fluid pressure to said rotor and a forwardly extending casing portion, a conduit

extending radially inward through one of said stationary vanes and axially forward in a wall of the casing to the forward casing end, a vanned throttle journaled in said casing for movement about the rotor axis to vary the effective delivery area of the spaces between the stator vanes, linkage means for adjustably positioning said throttle, a spring in the casing, arms in said casing having lateral pivot connections to the shaft, a flyweight roller carried by each of said arms, cam elements having surfaces inclined to the rotor axis, said rollers being adapted to ride laterally outward on said cam surfaces in response to the rotation of said shaft whereby said cam elements are moved axially forward, a push rod extending forwardly through said casing end and having a hollow portion in the casing journaled about said cam element, said push rod being axially movable in response to the lateral outward movement of said flyweight rollers to compress said spring against said casing end, first means operatively connecting said push rod with the linkage means carried by said throttle and responsive to axial movements of said push rod upon the outward movement of said flyweight rollers to convert said axial movement into a turning movement of said throttle in a closing direction, fluid pressure responsive means mounted on said casing end to receive fluid pressure from said independent source through said conduit, second means operatively connecting said fluid pressure responsive means to said linkage means to effect a turning movement of said throttle in a closing direction, a second spring, means connecting said second spring between the throttle and the casing to bias the throttle against said turning movements in an opening direction, means cooperating between the throttle and casing for adjusting the limits of said turning movement, and an independent fluid supply source including means for connecting said independent fluid supply to said housing, said connecting means being disconnectable upon the movement of said vehicle from a stationary position.

2. Turbine apparatus for use in a vehicle and adapted to be operated by an independent source of fluid pressure when said vehicle is stationary, and by ram pressure when said vehicle is in motion through a fluid medium, said independent source of fluid pressure being disconnected upon the initial movement of said vehicle from a stationary position, said apparatus comprising a housing, a vaned rotor, a shaft on said rotor for rotatably supporting said rotor in said housing, a vaned stator mounted in said housing and positioned forward of said rotor, said stator having a forwardly extending casing, a vanned throttle rotatably mounted on said casing and positioned forwardly of said stator, a ram pressure inlet disposed in said housing forwardly of said throttle, the vanes of said throttle being so constructed and arranged as to open or close the spaces between the vanes of said stator upon the relative displacement of the former to the latter to thereby control the amount of ram pressure passing from said ram pressure inlet through said stator and to said rotor, spring means connected between said casing and said throttle and normally biasing said throttle to a position where the spaces between the vanes of the stator are fully open, an inlet in said housing for receiving fluid pressure from an independent source of fluid pressure when said vehicle is stationary, means including nozzles formed in said housing for conducting fluid pressure from said inlet to

said rotor whereby said rotor may be rotated by said independent fluid pressure, a fluid pressure actuated mechanism, a linkage mechanism connecting said throttle to said fluid pressure actuated mechanism, a pressure conduit connecting said fluid pressure actuated mechanism to said inlet for the independent source of fluid pressure, said fluid pressure actuated mechanism and linkage mechanism being so constructed and arranged that when fluid pressure from said independent source is introduced into said inlet, the throttle is moved against the biasing effect of the spring means to a position whereby the vanes of said throttle fully close the spaces between the vanes of said stator, and a centrifugally operated mechanism mechanically associated with the shaft of said rotor and said linkage mechanism whereby said throttle is moved relative to said stator in response to the rotation of said rotor, said centrifugally operated mechanism normally being effective only after said independent source of fluid pressure is disconnected from said inlet upon the initial movement of said vehicle.

3. In a unit adapted to be carried by a movable vehicle and having a turbine operated by ram pressure when said vehicle is in motion through a fluid medium, said turbine including a housing having a ram pressure inlet, a vaned rotor mounted for rotation within said housing, a fixed stator mounted in said housing forwardly of said rotor and having vanes for directing ram pressure from said inlet to said rotor, a vaned throttle mounted in said housing forwardly of said stator and for rotary movement relative to said stator, the vanes of said throttle being adapted to open or close the spaces between the stator vanes to thereby control the delivery of ram pressure to said rotor, spring means biasing said rotary throttle to a position where the spaces between the vanes of the stator are fully open, and linkage means connecting said throttle to a governor carried by said turbine whereby said throttle is moved relative to said stator against the bias of said spring means to thereby control the ram pressure delivered from said inlet to said rotor in response to the rotational speed of said rotor, the combination with said turbine of means for rotating said turbine when said vehicle is stationary comprising, an independent source of fluid pressure, means for connecting said independent source of fluid pressure to said housing, nozzle means in said housing for directing fluid pressure from said independent source to the rotor of said turbine, a pressure responsive device actuated in response to fluid pressure from said independent source, and means for connecting said pressure responsive device to the linkage mechanism for rotating said throttle, whereby said throttle is moved against the bias of said spring means to move said throttle relative to the stator to a position whereby the vanes of the former close the spaces between the vanes of the latter, said means for connecting the independent source of fluid pressure to said housing being disconnectable upon the movement of said vehicle away from said independent source of fluid pressure.

4. In a turbine apparatus adapted for use in a movable vehicle and operable in response to ram pressure developed by the movement of said vehicle through a fluid medium, said apparatus including a housing defining a ram pressure inlet, a vaned rotor mounted for rotation in said housing, a fixed stator mounted in said housing forwardly of said rotor for directing ram pressure

to said rotor, a throttle mounted in said housing forwardly of said stator and for rotary movement relative thereto, spring means biasing said throttle to a first predetermined position relative to said stator, and linkage means connecting said throttle to a governor carried by said rotor whereby said throttle is moved between said first predetermined and a second predetermined position relative to said stator to thereby control the ram pressure delivered to said rotor, the combination with said turbine apparatus of means for operating said rotor when said vehicle is stationary, comprising an independent source of fluid pressure, a disconnectable connection between said independent source of fluid pressure and said housing, a plurality of nozzles formed in said housing for directing fluid pressure from said independent source to said rotor, pressure actuated means including a pressure conduit in communication with said independent source of fluid pressure and operable in response to said fluid pressure, and means for interconnecting said pressure actuated means to said linkage mechanism whereby the operation of said pressure actuated means in response to the initial flow of fluid pressure from said independent source rotates said throttle to its second predetermined position relative to said stator.

5. In combination, a unit adapted to be carried by a movable apparatus comprising a vaned rotor, an element driven by said vaned rotor, said vaned rotor being rotatable in response to fluid pressure, a vaned stator positioned forwardly of said rotor and having spaced vanes, a throttle positioned forwardly of said stator and having spaced vanes, said throttle being mounted for rotary movement relative to said stator, the vanes of said throttle being so constructed and arranged as to open or close the space between the vanes of said stator upon the relative movement of the former to the latter, means for biasing said throttle to a first predetermined position whereby the spaces between the vanes of said stator are fully open, a source of fluid pressure, means for connecting said source of fluid pressure to said unit, nozzle means for directing said fluid pressure between the vanes of said stator and against said rotor, fluid pressure responsive means connected with and operative in response to fluid pressure from said pressure source to move said throttle to a second predetermined position whereby the spaces between the vanes of said rotor are fully closed, and governor means carried by said element and operatively connected to said throttle, said governor means being operative in response to the speed of said element to control the relative position of said throttle to said stator in response to the speed of said element when the fluid pressure responsive means is inoperative.

6. In a turbine driven selectively by either of two unrelated sources of fluid pressure, the combination comprising a first conduit for delivering fluid pressure from one of said sources to said turbine, means responsive to turbine speed for regulating the fluid pressure delivered from said first conduit to said turbine, a second conduit for delivering fluid from the other of said sources to said turbine, and fluid pressure responsive means operated by the fluid pressure from said other source for moving said regulating means to a position closing said first conduit upon delivery of fluid pressure from said other source through said second conduit to said turbine.

7. In a turbine driven selectively by either of

two unrelated sources of fluid pressure, the combination comprising an inlet to said turbine, a first conduit for delivering fluid pressure from one of said sources to said turbine inlet, a valve mechanism to control the fluid pressure delivered from said first conduit to said turbine inlet, turbine speed responsive means, means operatively connecting said speed responsive means to said valve mechanism for regulating the fluid pressure delivered from said first conduit to said turbine inlet to thereby regulate the speed of said turbine, a second conduit for delivering fluid pressure from the other of said sources to said turbine inlet, fluid pressure responsive means operated by the fluid pressure from said other source, and other means operatively connecting said fluid pressure responsive means to said valve mechanism whereby said valve mechanism is moved to close said first conduit to said turbine inlet upon delivery of fluid pressure from said other source through said second conduit to said turbine inlet.

8. In a turbine driven selectively by two unrelated sources of fluid pressure, the combination comprising an inlet to said turbine, a first conduit for delivering fluid pressure from one of said sources of fluid pressure to said turbine inlet, a valve mechanism to control fluid pressure delivered from said first conduit to said turbine inlet, spring means biasing said valve mechanism in a first opening direction to open said first conduit to said turbine inlet, a second conduit for delivering fluid pressure from the other of said sources of fluid pressure to said turbine inlet, fluid pressure responsive means connected to said other source of fluid pressure, means operatively connecting said fluid pressure responsive means to said valve mechanism whereby the operation of the fluid pressure responsive means by its associated source of fluid pressure moves said

valve mechanism in a second direction to close said first conduit to said turbine inlet against the biasing force of said spring means when fluid pressure from said other source of fluid pressure is delivered through said second conduit to said turbine inlet, turbine speed responsive means, and means operatively connecting said speed responsive means to said valve mechanism whereby said valve mechanism is operated against the bias of said spring to regulate the delivery of fluid pressure from said one source of fluid pressure through said first conduit to said turbine inlet, to thereby regulate the speed of said turbine.

9. The combination defined by claim 8 in which the means for connecting said speed responsive means to said valve mechanism includes a lost motion linkage connection whereby said valve mechanism may be operated solely by said fluid pressure responsive means and independently of said speed responsive means.
